UNITED STATES PATENT OFFICE

ROY N. PIERSON AND CHARLES H. CARLSON, OF MINNEAPOLIS, MINNESOTA, AS-SIGNORS, BY MESNE ASSIGNMENTS, TO AMERICAN MULTIGRAPH CO., OF WILMING-TON, DELAWARE, A CORPORATION OF DELAWARE

LETTER FOLDING MACHINE

Application filed September 14, 1929. Serial No. 392,598.

This invention provides an extremely simple and highly efficient folding machine especially designed and intended for the folding of letter sheets in proper sizes to go into envelopes but it will, of course, be understood that the machine may be used more generally for folding paper sheets of various different kinds and the like. The machine is of such character that it is practically noiseless in action and has certain novel devices of an adjustable or rearrangeable character, whereby, sheets may be folded once to form two plies or twice to form three plies and, whereby, sheets of different width and length may be folded in the manner just indicated.

A commercial form of the machine is illustrated in the accompanying drawings wherein like characters indicate like parts throughout the several views.

20 Referring to the drawings:

Fig. 1 is a plan view of the improved machine;

Fig. 2 is a vertical section taken approximately on the line 2—2 of Fig. 1;

25 Fig. 3 is a section taken on the same line as Fig. 2 but with some parts broken away and others removed and the parts shown being on a larger scale than in Fig. 2;

30 Fig. 4 is a fragmentary plan view showing parts found in the vicinity of the line marked 4—4 on Fig. 3, some of the parts being broken away;

35 Fig. 5 is a side elevation with some parts broken away showing the folding roller mountings and immediately associated parts, the parts being on the same scale as in Fig. 3;

40 Fig. 6 is a detail of one of the roller journals some parts being sectioned on the line 6—6 of Fig. 5 and some parts being shown in full;

Fig. 7 is a detail in section taken on the line 7—7 of Fig. 3, some parts being broken away;

45 Fig. 8 is a side elevation showing in detail one of the gauge plates;

Fig. 9 is an end elevation of the gauge plates shown in Fig. 8;

50 Fig. 10 is a view in section showing a paper sheet such as a letter sheet folded twice or

into three ply, the thickness of the paper, of course, being exaggerated; and

Fig. 11 is a section on the line 11—11 of Fig. 3.

The various parts of the machine are 55 mounted on a frame made up chiefly of laterally spaced cast side plates 11 connected by various ties hereinafter noted and including a horizontally disposed feed table 12. The folding operation is performed by four 60 co-operating rollers, to wit: a central roller 13, an upper roller 14, a lower roller 15 and a rear roller 16. These rollers are preferably provided with rubber faces or exterior portions and the shafts 14^a, 15^a, and 16^a of rollers 65 14, 15 and 16 are journaled in movable bearings 17 that are movable in slots 18 and are spring-pressed toward the axis of the central roller 13 by coiled springs 19. The shaft 13^a of central roller 13 projects at one end and is 70 provided with a small pulley 20 and a relatively large pulley 21. By the springs 19, rollers 14, 15 and 16 are yieldingly held in frictional contact with roller 13 so that when the latter is driven all of the rollers will be 75 driven. A belt 22 runs over large pulley 21 and over a small pulley 23 carried by the shaft 24 of a small electric motor 25, the casting of which is secured to a bracket 26 pivoted to the frame work at 27 in such manner that proper tension on the belt 22 may be 80 maintained by adjustments of said bracket and motor.

In Fig. 3 a sheet of paper under the process of being folded marked Y is indicated by full lines and a second stage in the folding operation is indicated by dotted lines marked Y'. It should be noted that the feed table 12 is in such a horizontal plane that the sheets fed therefrom will be directed between the rollers 13 and 14. From between the rollers 13 and 14 the sheet Y is fed into the curved lower extremity of an upper inclined guideway 28 that is formed between vertically spaced upper and lower plates 29 and 30. The plates 29 and 30 are preferably of quite thin sheet metal secured at their side edges to extensions 11^a of the frame side plates 11. When the sheet Y is stopped in its upward and rearward movement in guideway 28, it will be 90 95 100

buckled and fed downward between rollers 13 and 16 and will be directed into a lower guideway 31 that is formed between upper and lower plates 32 and 33 which, like the 5 plates 29 and 30, are vertically spaced and secured at their edges to the frame side plates 11. When the sheet once folded upon itself is fed downward from rollers 13 and 16 into lower guideway 31 and is stopped in its down- 10 ward and rearward movement, it will be again buckled and then fed forward between the rollers 13 and 15 and onto a sort of inclined deck which, as shown, is made up of laterally spaced inclined bars 34 and 35 that are suitably secured at their lower ends to a receiving table 36 which, in turn, is mounted on the base and frame.

Overlying the inclined bars 34 and 35 is an inclined deflecting plate 37 pivotally mounted 20 on and frictionally held in set adjustments to brackets 38 secured on the side frames 11. Mounted adjacent to the receiving end of the table 36 and working between the lower ends of the bars 34 and beyond the delivery 25 ends of the latter, is a rotary packer. This packer, as shown, is in the form of a roller 39 having radially projected packer arms 40. The shaft 41 of the above noted packer is shown as journaled in bearing brackets 42 secured on the base plate 43 rigidly secured 30 to the lower portions of the side frames 11. At one end shaft 41 is provided with a pulley 44 over which the pulley 20 of central roller 13 runs a belt 45 so that the packer is 35 driven from said central roller. In Fig. 10 the letter sheet is shown as folded three ply and in Fig. 2 a plurality of pack of these folded sheets is shown as located on the receiving table 36 and pressed against a fol- 40 lower bracket 46 that is slidably mounted on said receiving table.

Stop devices of the novel construction are applied in connection with the inclined runways formed in the one instance between the 45 plates 29 and 30 and in the other instance between the plates 32 and 33 but as both of these stop devices are alike, the description of the one will answer for the description of the other. The upper plates 29 and 30 are 50 provided with longitudinally extended relatively wide slots 47 while the lower plates 32 and 33 are provided with underlying relatively narrow slots 48, see particularly Figs. 1 and 7. The numeral 49 indicates a plurality 55 of stop arms connected by a cross bar 50 so that it forms a sort of stop bracket with a plurality of free end stop surfaces 51 that are concentric to guide pins 52 that project laterally from the free ends of said arms.

The slots 47 in upper plates 29 and 30 are wide enough to permit guide pins 52 to freely pass therethrough. While the narrow lower slots 48 are only wide enough to permit the extreme free ends of the arms 49 to pass through the lower plates 32 and 33. The up-

per ends of arms 49 are pivotally connected by short bolts 53 to the free end portion of a yoke-like arm 54 that is pivotally connected to lugs 55, in the one instance on the upper end of the upper plate 29 and in the other instance on the lower end of plate 32. Thumb nuts 56 applied to the ends of the bolts 53 serve to frictionally lock the stop arms 49 in various different set adjustments.

For properly guiding the letter sheets to the folding rollers there is provided a pair of laterally adjustable gauge bars 57 which, as shown, have very thin inwardly projecting flanges 58 that rest closely on the feed table 12 and on which the edges of the sheet Y are adapted to rest. These gauge bars 57 are adjustably secured to a cross bar 59 by means of clamping screws 60 and co-operating lugs 61 arranged as best shown in Fig. 3.

As an important feature there is provided a fold cut-out device or means whereby the machine may be used to produce but a single fold in a sheet. For the support of two or more cam-acting cut-out deflectors, a transverse rod 63 is extended parallel to and just at the rear of the upper roller 14 and is secured at its ends to the frame side plates 11. These deflectors 62 are slidably mounted on rod 63 and are provided with set screws 64 by means of which they may be secured either in operative positions indicated by dotted lines in Fig. 1 or in inoperative positions indicated by full lines in Fig. 1. The top surfaces of deflectors 62 are curved so as to lie close to but not in frictional contact with roller 14. At their lower ends deflectors 62 are formed with concave extensions 62a that are concentric to the roller 13 but are spaced therefrom so as to leave a downward passage for the sheet Y.

Operation

For first illustration it will be assumed that the sheet Y is to be folded twice or three ply as shown in Fig. 10, and hence, that the cut-out deflectors 62 are adjusted to the outer ends of rod 63, as shown by full lines in Fig. 1, so that they will be out of the line of movement of the sheet Y as it passes from between the rollers 13 and 14. In this adjustment the sheet Y will pass from rollers 13 and 14 up into the first guideway 28 until its upper edge strikes the eccentric end surfaces of arms 49 whereupon the sheet will be buckled and fed double downward between rollers 13 and 16. From rollers 13 and 16 the once doubled sheet will be fed downward into second guideway 31 until it strikes the end surfaces of lower arms 49 whereupon the sheet will be again buckled and fed forward between rollers 13 and 15 and from thence onto the inclined deck made up of the inclined bars 34 and 35. The deflecting plate 37 prevents the folded sheet from being thrown too far upward and forward and causes the same to fold into the

range of action of the rotating packer 40 by which the sheets will be accumulated in a pack on receiving table 36 and fed forward against the movable follower bracket 46. It will, of course, be understood that the upper and lower stop arms 49 will be adjusted so that the sheets will be folded just at the desired places, and which matter of folding is usually determined by the size of the sheet and the size of the envelopes into which they are to be inserted. Here it is important to note that the end surfaces 51 which are concentric to stop pins 52 always presents stop surfaces for the sheets that are approximately at right angles to the sheets regardless of the various adjustments of the stop devices.

When it is desired to give the sheets Y but one fold, cut-out deflectors 62 are adjusted to the dotted line positions in Fig. 1 where they will be within the path of movement of the sheets and in such adjustments the front end of sheet Y as it moves from between rollers 13 and 14 will strike against the curved deflecting surfaces 62^a and without being folded at this point will be turned directly downward between rollers 13 and 16 and from thence will pass into the lower guideway 31 until its advanced edge strikes the stop surfaces 51 of the lower arms 49 and thereupon the sheets will be buckled and fed double forward between rollers 13 and 15. This operation, as is evident, will give the sheets but one fold and the once folded sheet will be delivered downward and packed onto the receiving table 36 by an operation previously described.

In actual practice, this machine has been found highly efficient for the purposes had in view.

40 What we claim is:

1. A folding machine comprising a group of folding rollers arranged as a central roller, an upper roller, a lower roller and a rear roller, a sheet guideway normally receiving the sheet from between said central and upper roller and having a stop for causing the said sheet to buckle downward between said central and rear roller, and lower sheet guideway receiving the sheet from between said central and rear roller and having a stop for causing said sheet to buckle between said central and lower roller, an inclined deck receiving the folded sheet from between said central and lower roller, a receiving table, and a packer operative on the folded sheets delivered from said deck and serving to pack the same on said receiving table.

2. A folding machine comprising a group of folding rollers arranged as a central roller, an upper roller, a lower roller and a rear roller, a sheet guideway normally receiving the sheet from between said central and upper roller and having a stop for causing the said sheet to buckle downward between said central and rear roller, and lower sheet guide-

way receiving the sheet from between said central and rear roller and having a stop for causing said sheet to buckle between said central and lower roller, and fold cut-out deflecting means comprising a cross rod at the rear of said upper roller, and a plurality of cam-acting deflectors slidably mounted on said cross rod to and from operative positions and serving, when in operative positions, to direct the sheet from between said central and upper roller directly downward, without folding, between said central and rear roller and from thence into said sheet guideway and from thence buckled and fed forward between said central and lower roller.

3. The structure defined in claim 2 in which the stops co-operating with said sheet guideways are independently adjustable for producing different width folds in the two folding actions.

4. The structure defined in claim 2 in further combination with a feed table aligned with the contacting portions between said central and upper roller, and laterally adjustable gauge bars applied on the upper surface of said table, said slideable cut-out devices being rendered inoperative when adjusted laterally outward of said gauge bars.

5. The structure defined in claim 1 in further combination with an adjustable deflecting plate located above said packer and serving to direct the folded sheets downward and subject to the action of said packer.

6. The combination with a group of folding rollers and a sheet guideway receiving the sheet from between the first two acting rollers and directing the same between the next acting rollers in buckled condition for folding, of an adjustable sheet-stopping device co-operating with said sheet guideway and comprising a pair of pivotally connected members one of which members is pivoted to a fixed support and the free end of the other of which members is projected through said guideway for adjustments longitudinally thereof.

7. The combination with a group of folding rollers and a sheet guideway receiving the sheet from between the first two acting rollers and directing the same between the next acting rollers in buckled condition for folding, of an adjustable sheet-stopping device co-operating with said sheet guideway and comprising a pair of pivotally connected members one of which members is pivoted to a fixed support and the free end of the other of which members is projected through said guideway for adjustments longitudinally thereof, the free end of said second member having a sliding pivotal connection with said guideway and having a stop surface that is concentric with said sliding pivot.

8. The combination with a group of folding rollers and a sheet guideway receiving the sheet from between the first two acting rollers

and directing the same between the next acting rollers in buckled condition for folding, of an adjustable sheet-stopping device co-operating with said sheet guideway and comprising a pair of pivotally connected members one of which members is pivoted to a fixed support and the free end of the other of which members is projected through said guideway for adjustments longitudinally thereof, said sheet guideway being formed between slightly spaced upper and lower sheets having aligned longitudinally extended relatively wide and narrow slots, and the free end portion of said stop-acting member having lateral projections affording a sliding pivotal connection between said member and lower plate, said pin being insertable through the slot of said upper plate but not through the slot of the lower plate, the free end of said stop member having a stop surface that is concentric to said pivot-forming lateral projection and extending downward through the slots of said lower plate.

In testimony whereof we affix our signatures.

ROY N. PIERSON.
CHARLES H. CARLSON.
